INTERFERENCE REDUCING AMPLITUDE
MODULATION DETECTOR

Donald D. Grieg, Forest Hills, N. Y., assignor to
Federal Telephone and Radio Corporation,
Newark, N. J., a corporation of Delaware

Application April 16, 1943, Serial No. 483,366

20 Claims. (Cl. 250—20)

1

This invention relates to radio translators and more particularly to the problem of limiting noise effects and other interfering and signal distorting voltage fluctuations occurring in radio transmission and reception of amplitude modulated signals.

One of the objects of my invention is to provide a method and means for greatly minimizing interference noise and other disturbances in radio transmission and reception of amplitude modulated signals.

Another object of my invention is to provide a method and means to remove noise interference and other disturbances occurring in the troughs of amplitude modulation carriers as well as distortion effects occurring at the peaks of the amplitude modulated signals.

Still another object of the invention is to provide a method and means for translating amplitude modulated waves for passage through intermediate stages having non-linear characteristics without objectionably distorting the waves.

Interference limiters heretofore proposed in connection with amplitude modulated signals for reducing the effect of impulse noises and similar voltage disturbances are not very satisfactory. Such limiters are operated by removing these interference voltages occurring during modulation which exceed the peak signal modulation. The disadvantage of such method of limiting is that the removal of noise cannot be complete since by operating the limiter to remove interference peaks occurring during the troughs of modulation would remove the modulation as well. Further, such limiting does not correct or avoid objectionable distortion due to non-linearity of amplifiers and other stages used in the transmitter or receiver, as the case may be.

According to my invention, I am able not only to remove noise interference occurring during modulation peaks but also during troughs of the modulation carrier wave thereby effecting an overall improvement in noise reduction in radio reception of amplitude modulated signals. I am also able, according to my invention, to use amplifier and other stages having non-linear characteristics without introducing distortion in the amplitude modulated carrier wave.

The reduction in noise interference I accomplish by limit clipping the modulated carrier between two limits selected where the sides of the undulations of the carrier wave vary in slope in substantially linear proportion to the amplitude variations of the corresponding undulations.

2

This produces a clipped or trapezoidal wave form, the edges of each cycle of which slope in proportion to the amplitude of the corresponding undulation of the carrier. By differentiating this wave form, alternate positive and negative pulses are produced one each for each cycle of the wave. These pulses are produced in amplitude in accordance with the steepness of the edges of each cycle of the trapezoidal wave so that they vary in amplitude according to the initial amplitude modulation of the undulation from which the cycle was produced. It therefore follows that the alternate positive and negative pulses thus produced may be detected the same as the undulations of the carrier. By gate clipping a narrow slice from the carrier, thereby limiting substantially all of the positive and negative undulations of cycles of the modulated carrier wave to predetermined values, substantially all of the interference fluctuations are eliminated thereby greatly minimizing noise interference.

To avoid distortion in amplifier and other stages of non-linear characteristics, I translate the carrier wave to the trapezoidal wave form by the limit clipping operation described above, pass the wave thus obtained through such stages and thereafter differentiate the wave to translate it into pulses defining signal envelopes substantially identical to the signal envelopes of the carrier wave as it was initially modulated. Since the non-linear characteristics of the intermediate stages do not in this way affect the slope relationship of the edges of the trapezoidal wave, such stages may now be used in accordance with my invention without introducing objectionable distortion.

For a further understanding of the invention, reference may be had to the following detailed description to be read in connection with the accompanying drawings, in which:

Fig. 1 is a block diagram of radio receiver according to my invention;

Fig. 2 is a graphical illustration of an amplitude modulated carrier;

Fig. 3 is a graphical illustration of a portion of the carrier greatly enlarged and showing the translation operations of my invention; and

Fig. 4 is a block diagram of a modified arrangement of the translating features of my invention.

Referring to Fig. 1, the radio receiver is shown provided with a receiver comprising a radio frequency stage 10 and an intermediate frequency stage 11. The radio frequency stage

is coupled to a receiving antenna 12. The wave translating feature of my invention includes a gate clipper 16 and a differentiator 18. The gate clipper 16 is preferably of the character arranged to limit clip the output wave of the stage 11 between two predetermined limits. A gate clipper of this character is disclosed in a co-pending application of E. Labin and myself entitled "Indicating and calibrating means" Serial No. 437,530, filed April 3, 1942. The gate clipper therein disclosed includes a diode-double-limiter tube having two limiting levels whereby a wave applied thereto is limited to the width determined by those limiting levels. This double limiting operation produces a trapezoidal wave form which is differentiated by the differentiator 18, the output of which is supplied to an audio detector 20 which preferably is of the peak riding detector character.

Should the gate clipper have a narrow band pass characteristic, the intermediate frequency is preferably "beat down" to a low intermediate frequency by a low intermediate stage comprising a suitable mixer and oscillator. This low intermediate frequency insures well-defined corners for the trapezoidal wave. Should a gate clipper be chosen having wide band pass characteristics, the low intermediate frequency stage may then be omitted.

Referring to Figs. 2 and 3, the interference limiting function of the invention will be explained. Assume that a carrier wave 22 initially modulated as indicated in Fig. 2 is received having noise fluctuating voltage occurring thereon as indicated by pulsations 23, 24, 25 and 26 on the enlarged view of the carrier in curve *a* of Fig. 3. These fluctuations are shown to illustrate the effect thereof on the initial envelope outline 30, 31 of the carrier wave. The distortion of the envelope is indicated by lines 32 and 33.

The first translation according to my invention comprises a clipping operation by the gate clipper 16. The gate is adjusted to take a slice from the carrier between predetermined limits such as indicated at levels 34 and 35. While I have shown these limiting levels to be equally spaced on opposite sides of the axis of the carrier, it will be understood that they may be selected to one side or the other of the axis if desired. The importance of this selection is that the sides of the undulations between the limiting levels should be such that slope thereof vary in substantially linear proportion to the amplitude variation of the corresponding undulations. It is preferable, therefore, that the limit clipping operation be made at the axis of the carrier.

The carrier portion thus clipped comprises the trapezoidal wave form 40, curve *a*. It will be noted that the noise pulsations of curve *a* as well as the signal amplitude variations of the undulations have been removed. It will also be noted that the time intervals covered by the sides of the trapezoidal wave comprise a very small percentage of the period of the carrier. For example, this reduction may amount to as great as 100 to 1 or greater depending, of course, on the breadth of the limits 34, 35. It will be further noted that the sides of the cycles 41, 42, 43, 44 etc. of the trapezoidal wave vary in slope from cycle to cycle in proportion to the amplitude variation of the corresponding undulations. If the gate opening of the clipper 16 is small compared to the carrier level, the change in slope of the wave cycles will be a linear function of the initial modulation of the carrier.

The differentiator 18 operates to translate the trapezoidal carrier cycles into pulses defining signal envelopes substantially identical to the signal envelopes of the carrier wave as it was initially modulated. This differentiation is shown in curve *b*. The positive pulses 52, 53 and 54 are produced by differentiation in response to the leading edges of the trapezoidal wave cycles 42, 43 and 44 and the amplitude of the pulses 52, 53 and 54 correspond in accordance with the steepness of the slopes of those edges. Likewise, the negative pulses 51a, 52a and 53a of curve *b* correspond in amplitude in accordance with the steepness of the trailing edges of the cycles of the trapezoidal wave. These positive and negative pulses, therefore, define as indicated at 60 and 61 the signal envelopes substantially identical as at 30 and 31 in the case of the undulations shown in curve *a*, Fig. 3 which it may be assumed illustrates the signal envelopes with which the carrier wave was initially modulated.

It is possible that some noise pulsations may occur on the carrier within the limits 34 and 35. Such pulsations, of course, will produce a variation in the slope of the corresponding cycle of the trapezoidal wave. Since the clipping operation cuts out a very high percentage of the carrier wave, the likelihood of noise fluctuating and other disturbing voltages occurring during the small time intervals of the leading and trailing edges of the cycles is exceedingly small.

In Fig. 4, I show the gate clipper 16 and the differentiator 18 separated by an intermediate stage 70. This arrangement illustrates further the utility of my invention. After the carrier wave is limit clipped as indicated by trapezoidal wave 40 of curve *a* (Fig. 3), the trapezoidal wave may be amplified or otherwise treated as may be desired by stages of non-linear characteristics without altering the relative slopes of the leading and trailing edges of the wave. Thereafter, the wave 40 may be translated into the pulses of curve *b* (Fig. 3).

This method of translation permitting the use of stages having non-linear characteristics either in the transmitting system or the receiver, is highly desirable because less caution regarding the linearity of such intermediate stages is then necessary.

While I have described the principles of my invention in connection with specific apparatus, it is to be understood that such apparatus is referred to by way of example only and not as limiting the scope of the invention as set forth in the objects and the appended claims.

I claim:

1. A method of minimizing the effects of distortion of the signal envelopes of amplitude modulated carrier waves comprising translating the undulations of an amplitude modulated carrier wave into trapezoidal wave form the slope of the side edges of which correspond proportionately to the amplitude of the corresponding undulations as they normally occur in absence of interference, and translating the trapezoidal wave form into pulses which vary in amplitude according to the slope of the leading and trailing edges of the trapezoidal wave form, said pulses defining signal envelopes substantially identical to the signal envelopes of the carrier wave as it was initially modulated.

2. The method defined in claim 1 wherein the first-mentioned translating operation includes limit clipping of the wave at levels selected near the axis of the wave.

3. The method defined in claim 1 wherein the first-mentioned translating operation includes clipping the wave at two limits selected at opposite sides of the axis of the wave.

4. The method defined in claim 1 wherein the first-mentioned translating operation includes limit clipping of the wave at levels selected near the axis of the wave and the second-mentioned translating operation includes differentiating the trapezoidal wave form.

5. The method defined in claim 1 wherein the trapezoidal wave form obtained by the first-mentioned translating operation is treated in at least one intermediate stage of non-linear characteristics prior to the second-mentioned translating operation.

6. The method defined in claim 1 in combination with a step for reducing the carrier wave to a low intermediate frequency before translation into trapezoidal wave form, thereby insuring well-defined corners for the trapezoidal wave.

7. A method of minimizing the effects of interference voltage fluctuations in the reception of an amplitude modulated carrier wave comprising limit clipping the modulated carrier wave between two amplitude limits within which the sides of the undulations of the carrier wave vary in slope proportional to the amplitude variations of the corresponding undulations as they normally occur in absence of interference, thereby removing a substantial portion of the upper and lower parts of the undulations together with at least the major portion of interference fluctuations occurring along the carrier, and differentiating the resulting clipped portion to produce alternate positive and negative pulses one each for each edge of a wave cycle, said pulses varying in amplitude substantially identically to the initial modulation of the carrier wave.

8. A system for minimizing the effects of distortion of the signal envelopes of amplitude modulated carrier waves comprising a first means to translate the undulations of the amplitude modulated wave into trapezoidal wave form the slope of the side edges of the wave cycles of which correspond proportionately to the amplitude of the corresponding undulations of the carrier wave as they normally occur in absence of interference, means to apply a carrier wave to said first means, and a second means for translating the trapezoidal wave form into pulses which vary in amplitude according to the slopes of the side edges of the wave cycles, said pulses defining signal envelopes substantially identical to the signal envelopes of the carrier wave as it was initially modulated.

9. The system defined in claim 8 wherein the first means includes a gate clipper arranged to limit clip the wave between two limits.

10. The system defined in claim 8 wherein the first translating means includes a gate clipper and the second translating means includes a differentiating circuit.

11. The system defined in claim 8, in combination with an intermediate stage through which the trapezoidal wave form is passed prior to application to said second translation means.

12. A system for minimizing the effects of interference voltage fluctuations in the reception of amplitude modulated carrier waves comprising means for limit clipping an amplitude modulated carrier wave between two amplitude limits where the sides of the undulations of the carrier wave vary in slope proportionately to the amplitude variations of the corresponding undulations as

they normally occur in absence of interference, thereby removing a large percentage of the upper and lower parts of the undulations of the carrier wave together with substantially all of any interference fluctuations occurring along the carrier wave, means to differentiate the resulting clipped portion of the carrier wave to produce alternate positive and negative pulses one each for each wave cycle, said pulses varying in amplitude according to the slope of the corresponding edges of the carrier wave so as to define signal envelopes substantially identical to the signal envelopes of the carrier wave as it was initially modulated, and means for deriving from at least certain of said pulses the envelope signals defined thereby.

13. A method of minimizing the effects of interference distortion in the reception of amplitude modulated carrier waves comprising translating the undulations of an amplitude modulated carrier wave into trapezoidal wave form the slopes of the side edges of which correspond proportionately to the amplitude of the corresponding undulations as they normally occur in absence of interference, translating the trapezoidal wave form into pulses which vary in amplitude according to the slopes of the leading and trailing edges of the trapezoidal wave form, said pulses defining signal envelopes substantially identical to the signal envelopes of the carrier wave as it was initially modulated, and deriving from said pulses the audio envelopes defined thereby.

14. A method of signal reception comprising translating the undulations of a signal amplitude modulated wave into trapezoidal wave form, the slope of the side edges of which correspond proportionately to the degree of signal amplitude modulation of the corresponding undulations, and translating the trapezoidal wave form into pulses which vary in amplitude according to the slope of the side edges of the trapezoidal wave, said pulses defining signal modulation envelopes substantially identical to the signal with which the wave was initially modulated.

15. The method defined in claim 14 wherein the first mentioned translating operation includes limit clipping of the wave at levels selected near the axis of the wave.

16. The method defined in claim 14 wherein the first mentioned translating operation includes limit clipping of the wave at levels selected near the axis of the wave and the second mentioned translating operation includes differentiating the trapezoidal wave form.

17. The method defined in claim 14 in combination with a step for reducing the carrier wave to a low intermediate frequency before translating into trapezoidal wave form, thereby insuring well-defined corners for the trapezoidal wave.

18. A receiver system for signal amplitude modulated waves comprising first a means to translate the undulation of a signal amplitude modulated wave wherein the slopes of the edges of the undulation in the vicinity of the zero axis thereof is proportional to substantially the instantaneous value of the amplitude modulating signal into trapezoidal wave form, the slope of the side edges of which correspond to the slope of the sides of the undulation in the vicinity of the zero axis, and a second means for translating the trapezoidal wave form into pulses which vary in amplitude according to the slope of the side edges of the wave cycles thereof, the resulting pulses defining a signal envelope substantially identical to the signal envelope of the signal with which that wave was initially modulated.

7
19. The system according to claim 18 wherein the first means include limit clipping means arranged to limit clip the wave between two amplitude limits.

20. A receiver system comprising means for limit clipping a signal amplitude modulated carrier wave between two amplitude limits between which the sides of the undulations of the carrier waves vary in slope proportionately to substantially the instantaneous value of the amplitude modulating signal, means to differentiate the resulting clipped portion of the carrier wave to produce alternate positive and negative pulses one each for each wave cycle, said pulses varying in amplitude according to the slope of the corresponding edges of the carrier wave to define signal envelope substantially identical with which said wave was initially modulated, and means for

5
deriving from at least certain of the pulses, the modulating envelope signals defined thereby.
